Primary Examiner — Catherine Tuttle(74) *Attorney, Agent, or Firm* — Jacox, Meckstroth & Jenkins(57) **CLAIM**

The ornamental design for the glass backboard with attached hemispherical deflectors, as shown and described.

DESCRIPTION

FIG. 1 is a front perspective view of the glass backboard with attached hemispherical deflectors showing my new design; FIG. 2 is a front elevation view thereof;

FIG. 3 is a side view thereof, the opposite side view being a mirror image; and,

FIG. 4 is a top view thereof, the bottom view being a mirror image.

The basketball hoop and hoop support shown in phantom in FIG. 1 are for illustrative purpose only and form no part of the claimed invention.

1 Claim, 1 Drawing Sheet**FIG. 1**

FIG. 2

FIG. 3

FIG. 4
